Inventor:

James S. Nelson.

UNITED STATES PATENT OFFICE.

JAMES S. NELSON, OF SPRINGFIELD, OHIO, ASSIGNOR TO I. M. HATCHER,
OF SAME PLACE.

TRIMMING FOR HALTERS AND BRIDLES.

SPECIFICATION forming part of Letters Patent No. 252,500, dated January 17, 1882.

Application filed May 6, 1881. (No model.)

To all whom it may concern:

Be it known that I, JAMES S. NELSON, a citizen of the United States of America, residing at Springfield, in the county of Clarke and State of Ohio, have invented certain new and useful Improvements in Halter-Trimming; and I do hereby declare the following to be a full, clear, and exact description of the invention, such as will enable others skilled in the art to which it 5 appertains to make and use the same, reference being had to the accompanying drawings, and to letters or figures of reference marked thereon, which form a part of this specification.

This invention relates to certain improvements in metallic fastenings, particularly designed for use in connection with halters, bridles, &c., as will be hereinafter more fully set forth; and it has for its object to provide a 15 simple and cheap method or means of uniting the several pieces which constitute horse-head gears of the character herein designated.

In the accompanying drawings, forming a part of this specification, like letters of reference indicate corresponding parts, in which—

25 Figure 1 is a perspective view of a halter constructed with my improved fastening, forming the means of uniting the several straps at their junctures; Fig. 2, a plan view of one form of the fastening which is used at certain 30 portions of the halter; and Fig. 3, a like view of a modified form of the same, which is adapted to be applied at other parts of the halter.

The letter A designates a halter, which is of the ordinary approved form.

35 The letter B indicates the fastening or coupling, which is applied to the juncture of the chin-strap and tie-rein, and which consists of a cast or other suitable metallic approximately rectangular frame, having about midway its 40 longest sides two inwardly-projecting lugs or ears, B'. Cast therewith, and forming a part of the said frame, are united bars E F G, the former of which is provided with a stud or pin, D, these bars being depressed below, or in a different plane from the frame B, for a purpose 45 hereinafter named.

The letter C indicates a similar metallic frame to the one just described, having a cross-bar, E', near one end, and a longitudinal bar, F', 50 united with the said bar E' and with one end of the frame proper. Each of the said bars is

provided with a projecting stud or pin, D', similar to the stud D, and which bars are also depressed beneath the surface or upper plane of their frame C.

To construct a halter in connection with my improved fastener, I apply the same in the following manner: First, at the juncture of the chin-strap and the tie-rein I apply the frame B by placing the same in an upright position 60 and passing the said chin-strap transversely across the frame B, passing it behind the sides of the frame and over the central bar, F. The tie-rein is then brought down from the throat-latch and carried behind the upper cross-bar 65 of the frame, over the bars E, F, and G, (as also the chin-strap,) passing down behind the lower bar or end of the frame proper, the said tie-rein having a perforation adapted to allow the stud D to project through and complete 70 the fastening. The application of the part C to the halter is made by passing the chin-and-nose strap transversely under and over its sides and the bar F', respectively, a hole being formed 75 therein for the passage of the lower stud D'. The cheek strap is then brought down behind the upper cross-piece of the frame and slipped over the upper stud D', a hole being provided therein for the purpose. At the intersection 80 of the cheek-strap and the throat-latch the connection is similarly made, as last described, the cheek-strap in this instance being applied, as is the chin-and-nose strap and the throat-latch, by passing it behind the end of the frame proper and over the bar E' and stud D'. 85

Having thus described my invention, what I claim as new, and desire to secure by Letters Patent, is—

A fastening for halters and bridles, consisting of an approximately rectangular frame 90 having a longitudinal piece running from one end thereof to and connecting with a cross-bar near the other end, the parts being provided respectively with a stud or pin and lying in a different plane from the frame proper, as shown 95 and described.

In testimony whereof I affix my signature in presence of two witnesses.

JAMES S. NELSON.
